FIG. 7

FIG. 8

UNITED STATES PATENT OFFICE.

ROBERT STEEL, OF PHILADELPHIA, PENNSYLVANIA.

APPARATUS FOR FILLING BOTTLES WITH LIQUIDS.

SPECIFICATION forming part of Letters Patent No. 337,883, dated March 16, 1886.

Application filed November 3, 1885. Serial No. 181,792. (No model.)

To all whom it may concern:

Be it known that I, ROBERT STEEL, a citizen of the United States, residing at Philadelphia, in the county of Philadelphia and State 5 of Pennsylvania, have invented certain new and useful Improvements in Apparatus for Filling Bottles with Liquids, of which the following is a specification.

My invention consists of a rectangular metallic tank open upon top for the reception of liquid, provided with a rod fixed centrally with the bottom, the rod being surrounded with a sleeve or tube to whose lower end is connected a plate, the superficial area of which 15 equals nearly that of the bottom, the under surface being faced with a plate of cork or rubber. This tube has upon its upper end a disk of circular form at right angles thereto, which engages with slots or openings upon 20 the under side of a hand-wheel which has a screw connection through its hub with a thread upon the upper end of the vertical rod, by which means, by the partial revolution of the wheel, the plate may be elevated above 25 the bottom of the tank sufficiently far to allow the liquid contained therein to flow into the filling-tubes, whose orifices are in the bottom, or to be brought down with its lower surface pressing tightly upon the upper ends 30 of said tubes, to shut off the flow of liquid. This filling tube or tubes, (as the case may be,) is provided with a valve situated at or near its top upon the exterior surface, having an 35 L-shaped orifice in its key communicating with an orifice in the upper side of the valve, that permits of communication with an opening in the wall of the tube directly in line therewith, to allow air to enter the tube upon the surface of the liquid, to cause the same to 40 flow downward or to close said opening when desired. The lower end of the filling tube is provided with a stop-cock, beneath which and centrally arranged therewith is a tube of diminished size for insertion into the neck of a 45 bottle, as more fully hereinafter described.

In the accompanying drawings, which make a part of this specification, Figure 1 is a front elevation of my improved apparatus with the front side of the tank removed. Fig. 2 is a 50 vertical section taken through the broken line $\alpha\alpha$ of Fig. 1. Fig. 3 is a plan view, the supporting-frame not being shown. Fig. 4 is a

plan view of the tank, the plate or plunger E, tube C, and hand-wheel B being removed. Fig. 5 is a face view of a portion of the tube 55 F. Figs. 6 and 7 are views, taken at right angles to each other, of the key f of the valve G. Fig. 8 represents a sectional view of the valve G and a portion of the tube F, showing the position the key f assumes when air is permitted to pass into the tube. Fig. 9 is a cross-sectional view of the hand-wheel D.

Like letters of reference in all the figures indicate the same parts.

A is a metallic tank of any suitable dimensions, which I prefer to construct of rectangular form, as represented. I support the same at proper height from the table by means of legs b, the upper end of which may be bolted or riveted to the tank. Projecting from the 70 center of the bottom of the tank is the rod B, having a screw-thread cut upon its upper end. Surrounding this rod is the sleeve or tube C, the upper end of which has a disk, c, with which openings in the lugs d d, on the under 75 side of the hand-wheel D, are caused to engage. This hand-wheel has a hub, e, that has a screw-thread connection with the upper end of the fixed rod B.

To the lower end of the tube C is attached 80 the plate or plunger E, having a plate of cork or gum rubber laid upon its under surface and secured thereto by any suitable means. There are braces m that serve to keep the plate in a level position.

By turning the hand-wheel D in the desired direction its connection by means of the openings in the lugs d with the disk c, rigid upon the tube C, and threaded hub e with the thread of the screw upon the end of the rod B, the 90 plate E is raised from or lowered with its under surface bearing upon the upper end of the filling-tube F, to admit liquid therein or to cut off the supply of the same. The pressure exerted upon the plate when its surface is 95 bearing upon the tube hermetically seals the upper end.

Attached to the outer surface of the filling-tube F, at a point near the upper end thereof, is the valve G, which has a key, f, provided 100 with openings i i, drilled at right angles to each other, (seen clearly in Figs. 2, 6, 7, and 8,) there being an orifice, K, in the body of the valve on top, and another orifice, l, in the face

or wall of the tube F contiguous to the valve. The purpose of this valve is to admit air into the tube F upon the surface of the liquid through the line of orifices, or to shut off 5 communication between the orifice *l* and the valve while the tubes are being filled.

H is a stop-cock or shut-off valve placed upon the lower end of the tube, to permit of the drawing off of the liquid contained therein.

16 To the lower end of this valve is connected the tube I of diminished size, to permit of its insertion into the neck of a bottle.

The operation is as follows: Previous to filling the tank A with liquid the plate or plunger

17 E is brought down with its under surface bearing tightly upon the upper ends of the filling-tubes F. The key *f* of the valve G is turned into the position seen in Figs. 1 and 2, which closes communication between the orifice *l* of

20 the tube and the valve. The stop-cock H is also closed. The tank A is then filled with the liquid which it is desired to bottle off, the bottle being placed with its neck surrounding the tube I. The plate or plunger E is raised

25 by turning the hand-wheel F in the direction of the arrow R, (seen in Fig. 3,) which, by its connection with the disk *c* through the openings in the lugs or brackets *d d* and threaded connection with the hub *e* of the wheel F to

30 the rod B, raises the tube C and its plate E, permitting the fluid to pass into and fill the tube F, sufficient space of time being allowed for the tube to become filled. The plate E is again brought down with its under surface

35 bearing tightly upon the ends of the tube or tubes by turning the hand-wheel in the direction of the arrow S. The key *f* of the valve G is turned one-fourth around into the position seen in Fig. 8, permitting the entrance of air

40 upon the surface of the fluid contained within the tube through the orifice K of the valve and orifices *i i'* of the key and *l* of the tube.

The stop-cock H is at the same time opened, and the fluid permitted to descend through the tube I into the bottle. The key *f* of the valve G is retained in the position shown in Figs. 1 and 2 while the tube F is being charged with liquid. Should the orifice *l* have direct communication through the valve at that time with the air, the fluid would escape 50 thereat and be lost. It is, however, necessary to supply air to the surface of the liquid contained within the tube, to cause it to descend into the bottle through the tube I, and the supply in the tank must be cut off to permit 55 but the charge to descend, which can be effected only by the entrance of a current of air upon its surface, the inner diameter of the tube being made of such size as will permit but sufficient fluid to be contained therein as will 60 fill a bottle of desired size.

In Figs. 1 and 2 a portion of the rods J J' are shown. These rods may extend across, connecting a series of the keys of the valves and stop-cocks when it is desirable to have a 65 number of filling-tubes connected with one tank, and the two rods may be connected together by a lever or suitable mechanism in such manner that one motion by the operator will open the series of keys of both at the 70 same time.

I claim as my invention and desire to secure by Letters Patent—

The tank A, constructed as described, having the tube C provided with plate or plunger 75 E, operated by suitable mechanism, in combination with the valve G, having orifices K, *i*, and *i'*, tube F, having orifice *l*, stop-cock H, and tube I, for forming apparatus for filling a bottle with a specified charge of liquid.

ROBERT STEEL.
